ABSTRACT

The viscosity index of a lubricating oil is improved by contacting the oil at elevated temperature and pressure with a catalyst having hydrogenation activity in the presence of hydrogen and in the presence of carbon monoxide.

11 Claims, No Drawings

TREATMENT OF LUBRICATING OILS

This invention relates to a method for improving the properties of lubricating oils. More particularly, it is concerned with the production of lubricating oils of improved viscosity index by contacting a lubricating oil fraction with a hydrogenation catalyst in the presence of hydrogen containing a minor amount of carbon monoxide.

The hydrogenation of lubricating oils to improve various characteristics is well known in the art. There are generally speaking, three major types of reactions involved in the hydrogenation of lubricating oils. These reactions depend to a considerable extent on the type of catalyst and the reaction conditions of temperature, pressure and space velocity. Hydrocracking is the most severe of the three types and usually is practiced on the heavier lube oil fractions such as those having a major portion of the fraction boiling above about 1,000°F. Hydrocracking effects a considerable amount of rupture of carbon to carbon bonds which results in an over-all reduction in the molecular weight of the lubricating oil and produces a considerable amount, depending on the severity of the treatment, of materials boiling below about 600°F. The product generally has an improved viscosity index but a considerable loss in yield is sustained.

A less severe type of hydrogenation is generally referred to as hydrotreating or hydrofining. Ordinarily in this type of reaction the catalyst has little if any cracking activity but a significant amount of molecular rearrangement occurs although the principal purpose is to saturate aromatics and convert organically combined sulfur and nitrogen to hydrogen sulfide and ammonia. The reactions are usually sufficiently severe to produce some low boiling material.

The least severe of the hydrogenation reactions is usually called hydrofinishing and its general purpose is to effect a slight reduction in the sulfur and nitrogen content of the charge material and to remove color bodies from the oil. Ordinarily in hydrofinishing there is little change in the over-all boiling range of the lube oil fraction feed and accordingly the yields of lube oil from this hydrogen treatment is generally within the range of about 90-100 percent. Hydrofinishing also has substantially no effect on the viscosity index of the charge.

While hydrogenation under severe conditions has been used to improve the viscosity index of a lubricating oil fraction, ordinarily the yields are undesirably low because in order to improve the viscosity index a reasonable amount, a sizeable portion of the feed is converted to low boiling oils thereby making the process uneconomical.

It is an object of this invention to improve the viscosity index of lube oil fractions. Another object is to produce lubricating oil fractions of improved viscosity index using conditions less severe than those necessary in the prior art to effect the same results. These and other objects will be obvious to those skilled in the art from the following disclosure.

According to our invention, lubricating oils of improved viscosity index are prepared by contacting a lubricating oil fraction with a halogen-free hydrogenation catalyst in the presence of hydrogen containing a minor amount of carbon monoxide.

The lubricating oil fractions used in the process of our invention may be obtained from various crude oils

and may comprise waxy distillates, deresined, decarbonized or deasphalted residual stocks, naphthalene base oils, hydrocracked residua and the like.

The reaction conditions in the hydrogenation zone 5 include temperatures between about 550° and 850°F., a preferred range being 600°-800°F. Suitable pressures include a range of about 500-2,000 psig. total pressure preferably 800-1,500 psig. The lube oil charge stock may be introduced into the reaction zone at a space velocity of between about 0.1 and 5.0 volumes of oil per volume of catalyst per hour, a preferred range being between 0.3 and 2.0 v/v/hr. Hydrogen may be introduced into the reaction zone at a rate between about 500 and 10,000 standard cubic feet per barrel of charge, a preferred range being from 1,000 to 7,500 scfb.

It will be appreciated by those skilled in the art that the specific reaction conditions are selected from the above ranges to effect the desired result. For example, a low temperature such as 600°F. coupled with a high space velocity such as 5 would result in a mild hydrofinishing reaction and would not have the desired effect. Similarly a low space velocity such as 0.1 coupled with a high temperature of 850°F. would result in undesirable overcracking. However, a low space velocity combined with a low temperature within the above defined ranges would be satisfactory. Additionally the conditions will vary from one charge stock to another but one skilled in the art should have no difficulty in selecting the specific reaction conditions to fit the particular circumstances.

The hydrogen need not be pure. Satisfactory results may be obtained using hydrogen having a purity as low as 65 per cent. Suitable sources of hydrogen are catalytic reformer by-product hydrogen, electrolytic hydrogen and hydrogen produced by the partial oxidation of a hydrocarbonaceous material followed by shift conversion and CO₂ removal.

40 The carbon monoxide may be introduced into the hydrogenation zone at a rate between about 0.01 and 10.0 mol per cent of the pressuring gas which is referred to herein as hydrogen. A preferred range is between 0.1 and 1.0 mol percent. Suitably, the hydrogen and carbon monoxide are introduced as a mixture.

45 The catalysts used in the process of our invention are composed of a hydrogenating component on a support. Suitable hydrogenating components comprise Group VIII metals such as the noble metals, e.g., platinum or palladium or iron group metals, e.g., cobalt and nickel and the compounds thereof. Optionally there may also be included in the hydrogenating component a Group VI metal such as molybdenum or tungsten or compounds thereof. When the hydrogenating component is composed of a noble metal it may be present in the catalyst in an amount between about 0.1 and 5 percent by weight of the catalyst composite preferably between about 0.2 and 2 wt. percent. When the hydrogenating component is an iron group metal it may be present in an amount between about 1 and 10 percent by weight of the catalyst composite preferably between 2 and 8 percent. The Group VI metal used in conjunction with the Group VIII metal may suitably amount to between about 5 and 35 percent by weight of the composite, a preferred range being between 8 and 25 percent. The hydrogenating components may be present as the metal or metal oxide or sulfide.

Suitable catalyst supports comprise refractory inorganic amorphous oxides such as alumina, silica, magnesia, zirconia, titania and the like and mixtures thereof. Preferably the catalyst support comprises a mixture of silica and alumina with the alumina being present in an amount ranging between 50 and 99 percent by weight. The support may also include a crystalline zeolite in de-
cationized or hydrogen form amounting to between about 0 and 50 wt. percent of the support. Suitable zeolites are those obtained by the removal of alkali metal ions from naturally occurring or synthetic zeolites having pore openings of 6-13A such as faujasite and zeolite Y and the like. Preferably the zeolite will have an alkali metal content of less than about 2.0 wt. percent. The catalyst should also be free of halogen.

The catalyst, in particulate form, may be used as a slurry, a moving bed or a fixed bed. Preferably the reaction is carried out by passing the reactants through a fixed bed of catalyst pellets. Reactant flow may be upward or downward through the bed or the gas may flow upwardly in countercurrent relationship to downwardly

The following examples are given for illustrative purposes only.

EXAMPLE I

This example shows the effect of carbon monoxide on the hydrocracking response of a dewaxed paraffin distillate using a nickel molybdenum on alumina catalyst. The hydrogenating compound in this instance is in the oxide form. The charge is a dewaxed paraffin distillate having a kinematic viscosity at 100°F. of 173.66 centistokes and at 210°F. 12.10 centistokes. The viscosity index of the charge is 49. The charge is hydrocracked by being passed over a catalyst containing 3.5 percent nickel and 18.5 percent molybdenum on alumina. Six runs are made, three at a temperature of 750°F. and three at a temperature of 825°F., one run at each temperature being free from carbon monoxide, one using hydrogen containing 0.5 mol percent CO and one using hydrogen containing 5.0 mol percent CO. Data on the reaction conditions and product appear below in Table I.

TABLE I

Run No.	1	2	3	4	5	6

flowing oil. In a preferred embodiment, the reactant stream, both gas and oil is passed downwardly through a fixed bed of catalyst extrudates, pellets or spheres.

It is known that under certain conditions the presence of carbon monoxide in a hydrocracking system has a detrimental effect on the cracking activity of the catalyst. However, this phenomenon was presumed to be present only with catalysts containing halogen and that CO had no effect on catalysts which did not contain halogen. For example, U.S. Pat. No. 3,531,396 discloses that the hydrocracking catalyst which contains no halogen is not appreciably affected by the presence of hydrogen containing as much as 10 percent CO. Surprisingly, it has been found that in the hydro-
gen treatment of lubricating oils using catalysts free of halogen, the presence of carbon monoxide does have an effect on the reaction. As a result of our invention, it is now possible to obtain the same effect as would be obtained by severe hydrogenation as by hydrocracking while obtaining substantially the same yield as would be obtained by hydrofining. This was particularly surprising in view of the prior art which indicated that in the hydrocracking of gas oils and the like, the activity of halogen-containing catalysts was suppressed and the activity of halogen-free catalysts was not affected by the presence of CO.

Under a given set of conditions, lubricating oils of higher quality, as measured by the viscosity index, may be prepared in the presence of carbon monoxide or if the catalytic hydrogens are run in such a manner as to manufacture a product of predetermined quality, higher yields may be obtained by means of the use of small amounts of carbon monoxide in the hydrogen.

From the above, it is apparent that under the milder conditions the presence of carbon monoxide led to higher yields as compared to runs in which carbon monoxide was absent. At the higher temperatures the inclusion of carbon monoxide afforded a product of higher viscosity index than was obtained in its absence.

EXAMPLE II

This example shows the effect of the presence of carbon monoxide on the hydrocracking response of a dewaxed distillate using a cobalt molybdate catalyst having a silica-alumina support. It also shows the residual effect of carbon monoxide.

The same charge as used in Example I was hydrocracked by being passed with hydrogen through a fixed bed of cobalt molybdate catalyst containing 2.8 wt. percent cobalt, 10.7 wt. percent molybdenum, 3.3 wt. percent silica and the balance alumina. In all, six runs were made, three at a temperature of 750°F and three at a temperature of 825°F. Runs 1 and 2 show the activity of the catalyst under standard CO-free operating conditions. In Runs 3 and 4 the hydrogen contained 0.5 mol percent CO. Runs 5 and 6 in which CO-free hydrogen was used show the residual effect of CO. In both temperature ranges the highest VI product was obtained when the hydrogen included carbon monoxide. The residual effect of carbon monoxide can be seen from Runs 5 and 6, the products of which are intermediate in quality between those of Runs 1 and 2 and Runs 3 and 4 in which carbon monoxide was added to the hydrogen. Data on the reaction conditions and product are set forth below.

TABLE 2

Run No.	1	2	3	4	5	6
Temperature, °F.	750	825	750	825	750	825
Pressure, psig	1800	1800	1800	1800	1800	1800
Space vel. v/v/hr.	1.0	1.0	1.0	1.0	1.0	1.0
Hydrogen rate, SCFB	4400	4400	4400	4400	4400	4400
CO in hydrogen, vol. %			0.5	0.5		
Product						
Yield, wt. %	87	82	80.9	75	85	79.5
Kin. Visc., cs.						
100°F.	120.8	51.28	70.85	21.78	83.27	30.45
210°F.	10.15	6.54	7.68	4.14	8.44	4.93
Viscosity index	62	82	74	100	73	91

It will be noted from Examples I and II that the product formed in the presence of carbon monoxide has an unexpectedly lower viscosity than the product formed in its absence since the magnitude of viscosity decrease is ordinarily taken as a measure of the extent of cracking. Since it would be expected in view of the discussion above that less cracking would occur in the presence of carbon monoxide, it would be expected that the product formed in its presence would be of higher viscosity than the product produced in its absence.

The residual effect of CO in Example II indicates that the CO need not be added continuously but may be added intermittently.

EXAMPLE III

This example shows the effect of the use of carbon monoxide during the mild hydrogenation of a hydro-cracked deasphalted residuum using 0.5 wt. percent palladium on a low sodium zeolite Y containing support.

*accounted for by the addition of hydrogen to the charge.

basis products dewaxed to nominal 0°F. pour point.

Under the conditions associated with the lower temperature runs, the inclusion of carbon monoxide improved the viscosity index of the charge about 7 units. Moreover, the yield was about 5 percent higher when the hydrogen treatment was conducted in the presence of carbon monoxide. Under the more severe temperature conditions, the viscosity index improvement was substantially the same in both the absence and presence of carbon monoxide but the inclusion of carbon monoxide led to a yield improvement of 27 percent.

We claim:

1. A process for moderating the hydrocracking of a lubricating oil fraction which comprises contacting said

fraction under hydrocracking conditions including a temperature between about 550° and 850°F., a pressure between about 500 and 5,000 psig, a space velocity between about 0.1 and 5.0 v/v/hr. and a hydrogen rate of between about 500 and 10,000 SCFB with a halogen-free hydrogenation catalyst in the presence of between about 0.1 and 10 mol percent carbon monoxide based on the hydrogen.

2. The process of claim 1 in which the hydrogenation catalyst comprises a Group VIII metal or compound thereof.

3. The process of claim 2 in which the Group VIII metal is palladium.

4. The process of claim 2 in which the Group VIII metal is nickel.

5. The process of claim 2 in which the Group VIII metal is cobalt.

6. The process of claim 1 in which the carbon monoxide concentration is between 0.2 and 5.0 mol percent.

7. The process of claim 1 in which the lubricating oil fraction is a raw distillate.

8. The process of claim 1 in which the lubricating oil fraction is a deasphalted residuum.

9. The process of claim 8 in which the lubricating oil fraction is a hydrocracked deasphalted residuum.

10. The process of claim 1 in which the catalyst comprises a refractory amorphous inorganic oxide support.

11. The process of claim 10 in which the support comprises a crystalline zeolite having uniform pore openings of between 6 and 13 Å and an alkali metal content of less than 4.0 wt. percent.

* * * * *
